UNITED STATES PATENT OFFICE

109,618

DESIGN FOR A COMBINATION BOTTLE AND STOPPER THEREFOR

Tommi Parzinger, New York, N. Y., assignor to Hattie Carnegie, Inc., New York, N. Y.

Application November 1, 1937, Serial No. 72,576

Term of patent 14 years

To all whom it may concern:

Be it known that I, Tommi Parzinger, a citizen of Germany, residing at 320 East 57th Street, city, county, and State of New York, have invented a new, original, and ornamental Design for a Combination Bottle and Stopper Therefor, said combination being particularly adapted for perfumes and cosmetics, of which the following is a specification, reference being had to the accompanying drawing, forming part thereof.

Fig. 1 is a front elevational view of a combination bottle and stopper therefor, showing my new design;

Fig. 2 is a rear elevational view; and

Fig. 3 is a bottom plan view thereof.

I claim:

The ornamental design for a combination bottle and stopper therefor, as shown.

TOMMI PARZINGER.
